METHOD FOR REMOVING CONTAMINATION
FROM PRECIPITATES

Glenn W. Stahl, Waynesboro, Va., assignor to the United States of America as represented by the United States Atomic Energy Commission

No Drawing. Application September 7, 1951
Serial No. 245,637

11 Claims. (Cl. 23—14.5)

The present invention relates in general to improvements in processes for the production of plutonium, and more particularly to a washing method for the removal of contamination, especially uranium fission products, from carrier precipitates, bearing plutonium values, which are contaminated therewith.

As is known, plutonium—more specifically the 239 isotope of plutonium—is conventionally produced by transmutation of uranium effected by subjecting natural uranium to neutron irradiation. In current practice, the product thus obtained is ordinarily a mass of irradiated uranium containing a concentration of the order of 0.02% plutonium and a like concentration of uranium fission products. However, the presence of even small amounts of uranium or fission products usually interferes with the ultimate applications of plutonium. This is especially true with respect to the fission products—isotopes having atomic numbers ranging predominantly from 30 to 63—which are in general highly radioactive and therefore greatly deleterious from both physiological and technical standpoints. Accordingly, for successful utilization, the small proportion of plutonium so produced must be isolated and recovered from the materials associated with it in the irradiated mass.

Employing customary procedures, initially the plutonium, accompanied by much of the fission product contamination, is quite readily separated from the bulk of uranium. This may be done by dissolving the irradiated mass in aqueous nitric acid, solubly complexing uranium with sulfate ion, and removing from solution the often-minute concentration of plutonium in its tetravalent state by carrier precipitation upon bismuth phosphate. Then, for the exceedingly difficult tasks of isolating plutonium from the fission product contamination and concentrating the so decontaminated plutonium, conventional procedures involve pluralities of cycles of separate selective carrier precipitations of plutonium and of fission products from aqueous solution. Preeminent among such carrier precipitation cycles are those employing bismuth phosphate and those employing lanthanum fluoride: first to selectively carry plutonium and then, under altered conditions, to selectively carry fission products. It is with such carrier precipitation operations, especially those employing bismuth phosphate, that the present invention is concerned.

Considering the general, conventional bismuth phosphate cycle in greater detail, bismuth phosphate characteristically carrier precipitates tetravalent plutonium highly efficiently, but leaves hexavalent plutonium remaining in solution. Concurrently, bismuth phosphate carries some fission product species and other contaminants well, and some poorly, under both plutonium oxidation conditions involved. By virtue of these considerations, processing plutonium through successive bismuth phosphate carrier precipitation operations while alternating the plutonium oxidation state between the tetravalent and hexavalent states will gradually reduce the fission product contamination. That is, in more detail, bismuth phosphate is precipitated in an aqueous nitric acid solution containing the plutonium in tetravalent state, whence plu-

2

tonium is co-precipitated, leaving behind in solution a substantial portion of fission products and other sources of contamination; the carrier precipitate containing plutonium is then separated from its supernatant, dissolved to form an aqueous nitric acid solution and the plutonium oxidized to the hexavalent state. In the resulting solution, bismuth phosphate is again precipitated, ordinarily carrying down a substantial portion of fission products and other contaminants, and leaving a preponderant portion of the plutonium in solution. After removing the resulting contaminant-bearing precipitate, the supernatant solution, containing the bulk of the original plutonium, may be treated by another bismuth phosphate carrier precipitation of plutonium in tetravalent state, or other plutonium purification operation. This cycle, comprising alternately carrier precipitating plutonium, and carrier precipitating contaminants, is conventionally repeated a number of times until sufficient plutonium decontamination is effected. The general aspects of the lanthanum fluoride cycle are substantially identical with those just outlined for the bismuth phosphate cycle. These general cycles comprise the inventions and concepts of others, and do not, *per se*, constitute a part of the present invention. Details of these processes are more fully set forth in co-pending applications as for example: S. N. 478,570, filed March 9, 1943, now Patent No. 2,799,553, granted July 16, 1957, and 519,714, filed January 26, 1944, now Patent No. 2,785,951, granted March 19, 1957, both in the names of Thompson and Seaborg, and in applicant's co-pending application S. N. 597,593, filed June 4, 1945, for "Use of Fluo-Reagent," now titled "Enhancing Precipitations by Applying Soluble Complex Fluorine-Containing Reagents." Accordingly, reference is made to these co-pending applications, and as well to the specific examples hereinafter presented, for further details concerning these conventional processes.

While such carrier precipitation procedures ultimately produce substantially pure plutonium, their efficiency could desirably be much higher. This results from the fact that in both the plutonium, and the contaminant, carrier precipitations a considerable portion of the contaminants, especially gamma-radiation emitters, ordinarily accompany the plutonium, precipitating with plutonium in the former precipitation and remaining in the supernatant in the latter. Unfortunately, however, with each repetition of a purification cycle for the purpose of further partial removal of the accompanying contamination, an increment of plutonium is removed with the separated contaminant fraction. As a consequence, even after its extensive recycling and reprocessing of contaminant fractions for plutonium recovery, relatively large amounts of valuable plutonium must finally be discarded with contaminant wastes. Furthermore, since the extreme radioactivity of the fission products normally requires that such processing be conducted behind massive radiation shielding and by remote control techniques until the fission product contamination is reduced to a tolerable radiation level, the persistence of substantial fission product contamination through repeated purification operations has adversely compelled the purification operations to be encumbered with such apparatus and operational complexities throughout many stages of processing. Therefore, it has been highly desired, in this particular art, that efficient methods for supplementing these conventional carrier precipitation procedures be found in order to more quickly and thoroughly reduce or eliminate such contamination of plutonium.

Accordingly one object of the present invention is to provide a new and improved method for removing contamination, particularly contaminating uranium fission products, from precipitates containing the same.

Another object is to provide such a method particularly

adapted to selectively removing such contamination from plutonium-bearing carrier precipitates, especially bismuth phosphate carrier precipitates, containing the same.

A further object is to provide such a method particularly effective for removing gamma radiation emitting species of uranium fission products, so contaminating plutonium-bearing bismuth phosphate carrier precipitates.

Still another object is to provide such a method adapted to beneficially supplement conventional carrier precipitation procedures so as to increase decontamination efficiency, toward reducing the number of carrier precipitation cycles required for effective decontamination.

Still a further object is to provide such a method, simple in operation, adapted to be incorporated readily in such conventional procedures with a minimum of equipment and operational changes.

Additional objects will become apparent hereinafter.

In accordance with the present invention, contaminating uranium fission products are removed from carrier precipitates, especially plutonium-bearing bismuth phosphate carrier precipitates, containing the same, by washing the precipitates with an aqueous solution of ammonium hydrogen fluoride. Applicant has discovered that an aqueous solution of ammonium hydrogen fluoride (this being identical with an aqueous solution of ammonia and hydrofluoric acid in a molar ratio of 1:2), and solutions of ammonia and hydrofluoric acid in molar ratios other than 1:2, are uniquely effective in washing gamma-radiation-emitting uranium fission product contamination from plutonium-bearing bismuth phosphate carrier precipitates, with very little if any simultaneous removal of plutonium values therefrom. Not only are such solutions evidently selective solvents for the contaminants but not for the plutonium values or the carrier precipitate, but they have further proven not to disrupt the bonding of the minute amounts of plutonium values to the precipitated carrier compound, even upon a slurring of the carrier precipitate therein. For instance, it has been found that three washes, of only one minute each, of a bismuth phosphate carrier precipitate bearing bearing plutonium values and uranium fission products, with an aqueous solution of ammonium hydrogen fluoride (0.5 M in F⁻), removed 92.7% of the gamma radiation activity associated therewith, while removing only 0.1% of the plutonium values. The utter simplicity of this operation makes it readily applicable to conventional carrier precipitation processes, and it has been found when so applied the method affords marked increase in the plutonium decontamination efficiency of those processes, so as to afford reduction in the number of decontamination stages required and material alleviation of the apparatus and operational complications occasioned by the gamma radioactivity of the contaminants.

In conducting the present process, the exact compositions of satisfactory solutions employed for the washing operation are subject to considerable variation. It has been found, as an optimum, that solutions of ammonia and hydrofluoric acid in molar ratio of 1:2 (such being, in effect, solutions of the compound, ammonium hydrogen fluoride, NH₄HF₂) are the compositions generally affording the best decontamination. Yet, good decontamination factors are obtainable upon washing with solution of different NH₃ to HF molar ratios (such being, in effect, solutions of ammonium hydrogen fluoride also containing either ammonia or hydrofluoric acid); among these NH₃ to HF ratios of the order of 1:2 to 1:4 are found preferable. Likewise, various wash-solution concentrations may be used; while concentrations within the approximate range of 10% to 20% (by weight) are deemed preferable, with 10% appearing to be the optimum, effective results have been obtained with solutions even more dilute than 1%. In general, the washing operation proceeds quite satisfactorily at convenient room temperature.

Since, evidently, no significant disruption of the bond-

ing of the plutonium values to the bismuth phosphate carrier precipitate obtains, the washing operation itself may be effected by virtually any conventional precipitate washing procedure. Slurrying the carrier precipitate with the wash solution, followed by separation of the bulk of the wash liquid, along with the removed contamination contained therein, from the washed solid by centrifugation, filtration, or the like, has proven to be eminently satisfactory; preferable slurring time is of the order of 15 to 30 minutes at room temperature. In particular, in plant-scale plutonium production operations, wherein it is customary to separate the contaminated, plutonium-bearing carrier precipitate from the solution in which it was originally precipitated, by centrifugation, it has been found advantageous merely to add applicant's wash solution to the separated precipitate while it is still in the centrifuge bowl, in amount sufficient to form a loose slurry, and, after several minutes contact in the bowl with mild agitation to keep the precipitate suspended, centrifuging to separate the solid precipitate from the wash solution. Alternatively, the washing may well be accomplished by percolating the wash solution through a bed of the precipitate, or by various other methods known, or which will immediately become apparent, to those skilled in the art. Although a single wash effects substantial removal of the contamination, ordinarily even more contamination may be removed by repetition of the washing operation. In employing such multiple washing procedure, three washings appears to be the optimum number. It is normally desirable that the washing with applicant's reagents be followed by a washing with water to purge the precipitate of any remaining wash solution and any contamination that may be dissolved therein. Since washing the carrier precipitates with water is a practice oftentimes included in conventional operation, applicant's washing method may be incorporated in lieu of or supplementary to such conventional water washing; in fact, alteration of existing processing procedures may be minimized, where this is desirable, by merely dissolving applicant's reagent in the water which would otherwise be used alone to wash the precipitates.

In application of the instant washing method to repetitive bismuth phosphate carrier precipitation cycles in conventional plutonium decontamination operations, it is most desirable that the more highly contaminated plutonium-bearing bismuth phosphate precipitates, evolved in the earlier stages of the operation, be so washed, in order to more quickly remove the bulk of contamination from association with the plutonium; furthermore, since a reduction of gamma contamination to an order of at least as low as 10⁻⁷ of original is generally required in conventional plutonium production, the washing in this manner of every plutonium-bearing bismuth phosphate precipitate accordingly is particularly beneficial. However, in such application to conventional decontamination cycles it has been found that a special precautionary measure is advisable, in view of the fact that there is generally some conversion, in the precipitates, of bismuth phosphate to bismuth trifluoride, upon washing with applicant's reagents. The degree of conversion of the precipitate to fluoride varies, depending upon the extent of washing (volume used, time of contact, number of washes, concentration of the solution, and the like). While there is evidently no disrupting of the bonding of the carried plutonium values to the precipitate, despite this conversion to bismuth trifluoride, the fluoride present in the precipitate may detrimentally interfere in later steps in the cycle, particularly the subsequent step of carrier precipitating contaminants with bismuth phosphate while maintaining the plutonium values dissolved in hexavalent oxidation state. It has been found, however, that the precipitate is readily purged of fluoride ion, when necessary, by washing with an aqueous alkali hydroxide solution. The bismuth trifluoride precipitate is readily converted in this manner to a bismuth hydroxide precipitate, where-

upon it still retains the plutonium values bound thereto, while the fluoride ions are effectively carried away in the hydroxide wash solution, since bismuth hydroxide is more readily soluble in nitric acid than is bismuth phosphate, such conversion actually enhances, rather than interferes with, the normal subsequent dissolution of the plutonium-bearing carrier precipitate in that acid. A single wash with an aqueous solution of KOH or NaOH solution of concentration of the order of 15% (by weight) has been found to be satisfactory for this purpose.

Further illustration of the quantitative aspects and preferred conditions and procedures of the present method is provided in the following specific examples. Example 1 demonstrates generally the application of the present washing method to a conventional bismuth phosphate carrier precipitation operation for plutonium decontamination, and the relative effectiveness in removing contamination of several of applicant's reagents as compared with water and hydrofluoric acid.

EXAMPLE 1

A bismuth phosphate precipitate carrying plutonium values and contaminated with uranium fission products was derived in accordance with the following conventional procedure:

(a) Natural uranium metal subjected to chain uranium fission reaction for a period sufficient to transmute approximately 0.025% thereof to $^{94}\text{Pu}^{239}$, and stored to permit radioactive decay;

(b) Thereafter, uranium metal dissolved in stoichiometric amount of 13 N HNO_3 , then diluted with water to form a 31.4% uranyl nitrate solution;

(c) Solution made 1 N in H_2SO_4 , 0.1 M in NaNO_2 , then diluted with water to twice its volume, and heated to 75° C., to reduce Pu to tetravalent state;

(d) 2.5 grams/liter of Bi^{+++} added; H_3PO_4 added to 0.6 M over a period of two hours; digested one hour at 75° C.; then the formed BiPO_4 carrier precipitate separated from its supernatant by centrifugation.

Equal amounts of the resulting precipitate carrying plutonium values but substantially no uranium values, and contaminated with uranium fission products, were washed three times with either water, hydrofluoric acid solution, or ammonium hydrogen fluoride solution, as indicated. Each wash was conducted by slurring the precipitate in approximately 15 gallons of the particular wash solution per pound of precipitate for approximately one minute, and then separating the precipitate from the wash solution by centrifugation. For each wash solution, the amount of plutonium and gamma contamination removed by the washing procedure was determined analytically; the results are presented in Table 1 below.

Table 1.—Washing of Pu-carrying BiPO_4 precipitates

Run	Wash Solution	Percent of Total Plutonium Removed in Wash Solution	Gamma Decontamination Factor ²
A	H_2O (control)	0.3	5.8
B	HF 0.5 M (control)	3.4	7.4
C	$\text{NH}_3:\text{HF}=1:4$	0.0	23.3
D	$\text{NH}_3:\text{HF}=1:2$	0.1	13.7
E	$\text{NH}_3:\text{HF}=3:4$	1.9	7.3
F	$\text{NH}_3:\text{HF}=1:1$	4.1	6.5

¹ Mole ratio: F- concentration 0.5 M in each case.

² Gamma decontamination factor = $\frac{\gamma \text{ activity before washing}}{\gamma \text{ activity after washing}}$

The efficacy of the present washing method in removing gamma contamination is clearly evidenced by the results set forth in Table 1. The preferability of employing molar ratios of ammonia hydrofluoric acid within the range 1:4 to 1:2 is also apparent. Investigation of the effect of using a longer washing period is made in following Example 2.

EXAMPLE 2

Runs C and D of Example 1 were repeated, but the washings were made by slurring for three 20 minute, instead of 1 minute periods. The gamma activity was measured between each wash; results are presented in Table 2 below.

Table 2.—Distribution of gamma activity throughout precipitate washing

Wash Solution, $\text{NH}_3:\text{HF}$ Mole ratio	Measured Distribution of Gamma Activity (in percent of total in precipitate)					
	First Wash	Second Wash	Third Wash	Washed Precipitate	Total in Washes	Gamma Decontamination Factor
1:4	82.3	4.3	0.5	3.4	87.1	29.4
1:2	70.5	10.9	0.6	1.8	82.0	55.5

The results in Table 2 illustrate the greater gamma decontamination afforded by the longer washing periods. It is also noteworthy that while under the conditions of extremely short slurring time in Example 1 the solution of molar ratio 1:4 afforded the best decontamination factor, yet with the washing period of more practical duration in Example 2, the solution of molar ratio 1:2 (ammonium hydrogen fluoride) exhibited marked superiority.

In both of the foregoing Examples 1 and 2, the washings were made very dilute solutions, i. e. ca. 1% (by weight) concentration. In the following Example 3, the effect of concentration of the wash solution is studied. Also, in this instance, wash solution volumes of only ca. 1.5 gallons per pound of precipitate, found more convenient in plant-scale operations for washing directly in the centrifuge bowl, were used.

EXAMPLE 3

A series of plutonium-bearing bismuth phosphate carrier precipitates were derived in accordance with the procedure outlined in Example 1. In each case the entire precipitate was subjected to 3 washes with an NH_4HF_2 solution, followed by a final wash with water, employing the slurring procedure employed in the preceding examples. The volume of wash solution used in each wash was ca. 1.5 gallons per pound of precipitate. The washing times were 20 minutes for the first wash, and 10 minutes each for the second and third washes; the water wash was of similar short duration. The solution concentrations of 2, 5, 10, and 20%, respectively, were employed in the four runs made. The gamma decontamination factors were calculated on the basis of gamma contamination in the original solution of irradiated uranium; the cumulative decontamination factors which had been achieved upon the end of each step are tabulated in Table 3 below.

Table 3.—Effect of NH_4HF_2 concentration in washing

NH_4HF_2 Concentration (per cent by wt.)	Cumulative Gamma Decontamination Factors			
	2	5	10	20
Wash Contact Time (min.)	20-10-10	20-10-10	20-10-10	20-10-10
Step:				
(1) Carrier Precipitation	7.7	6.6	6.6	9.1
(2) After one wash	8.4	9.7	17.2	24.0
(3) After two washes	8.8	13.6	66	28.2
(4) After three washes	9.2	17.5	125	31.4
(5) After three NH_4HF_2 washed plus water wash	9.2	19.8	146	142
Improvement in Decontamination Factor Due to Washes	1.2	3	22	15.6

The preferability of employing wash solution concentrations within the range of 10 to 20%, and the apparent optimum of 10%, are plainly indicated in Table 3.

Analysis of the ammonium hydrogen fluoride wash solutions after washing has revealed that a predominate proportion of the uranium fission products contamination thereby removed consisted of zirconium and niobium species, which species, incidentally, normally constitute over two thirds of the gamma contamination normally encountered in plutonium production. The efficacy of the present process for removing specifically zirconium and niobium activity is specially studied in Example 4, wherein the combined zirconium and niobium activity was separately traced through the washing operation.

EXAMPLE 4

Two bismuth phosphate precipitates carrying plutonium values were derived and washed in a manner similar to that employed in Example 3; while three washes with NH_4HF_2 were employed, no wash with water was used; washing times were 20, 10, and 10 minutes, respectively, and wash solution volumes were 15, 7.5 and 7.5 gallons per pound of precipitate, respectively. In both cases the washing was done at room temperature. The concentration of ammonium hydrogen fluoride was 0.5 M in each instance, and the precipitates were stirred during washing with a mechanical stirrer. The amounts of plutonium and of zirconium-niobium activity, expressed in percentage of the amount originally present in the initial solution of irradiated uranium, were determined and are tabulated in Table 4 below.

Table 4.—Removal of zirconium-niobium activity

Fraction Analyzed	Amount of Plutonium		Amount of Zr-Nb Activity	
	Run A, percent	Run B, percent	Run A, percent	Run B, percent
Carrier Ppt'n. Supernatant	4.1	3.8	90	90
First Wash Waste	0.2	0.2	9	8
Second Wash Waste	0.1	0.1	1.4	1.2
Third Wash Waste	0.02	0.04	0.1	0.1
Final Washed Precipitate	95	96	0.37	0.26
Overall Zr-Nb Decontamination Factor			270	384

While this invention has been described with particular reference to its application the processing of specifically Pu^{239} through conventional bismuth phosphate carrier precipitation cycles, it is inherently of much wider applicability. The present method is equally as well adapted to such processing of other plutonium isotopes, for example the non-fissionable Pu^{238} isotope. Pu^{238} , valuable as a radioactive tracer, may be derived from non-fissionable sources through application of bismuth phosphate carrier precipitation processes wherein the present method may be advantageously employed for removing contamination associated with the precipitate. Furthermore, applicability is not at all restricted to the conventional carrier precipitations cycles outlined, but beneficially extends to the removal of contamination from plutonium-carrying precipitates, as exemplified by bismuth phosphate carrier precipitates, generally, irrespective of the specific processes in which they arise.

More broadly, the present invention is not necessarily limited to plutonium processing. The invention provides a new and improved method for removing contamination, especially gamma-emitting radioactive species, from bismuth phosphate and the like carrier precipitates. As such, the method is efficacious in accomplishing such results regardless of whether the precipitates are carrying plutonium or not. For example, this method may be employed for the removal and recovery from bismuth phosphate carrier precipitates of cyclotron-produced radiozirconium and/or radioniobium values being carried

thereupon in their production. Various additional applications of the instant method will become apparent to these skilled in the art. It is therefore to be understood that all matters contained in the above description and examples are illustrative only and do not limit the scope of the present invention.

Cross-reference is made to applicant's co-pending application, Ser. No. 597,593, filed June 4, 1945, for Use of Fluo-Reagent, directed to improving similar carrier precipitation operations in different manners, with different types of fluorine-containing reagents.

What is claimed is:

1. A method for removing uranium fission products from a bismuth phosphate carrier precipitate which has carried the same from aqueous solution therewith, which comprises washing the precipitate with an aqueous solution of ammonium hydrogen fluoride.

2. A method for removing gamma-radioactive uranium fission products from a bismuth phosphate carrier precipitate which has carried the same from aqueous solution therewith, which comprises washing the precipitate with an aqueous solution of ammonium hydrogen fluoride.

3. A method for removing zirconium values from a bismuth phosphate carrier precipitate bearing the same, which comprises washing the precipitate with an aqueous solution of ammonium hydrogen fluoride.

4. A method for removing niobium values from a bismuth phosphate carrier precipitate bearing the same, which comprises washing the precipitate with an aqueous solution of ammonium hydrogen fluoride.

5. In a process for the separation and decontamination of plutonium values from an aqueous solution containing the same together with contaminating uranium fission products, comprising precipitating bismuth phosphate therein while maintaining said plutonium values in tetravalent oxidation state, to thereby carrier precipitate said plutonium values therewith, and thereafter separating the resulting plutonium-carrying precipitate from its supernatant solution, the improved method for removing contaminating uranium fission products from the separated carrier precipitate, which have accompanied the same, which comprises washing the precipitate with an aqueous solution of ammonium hydrogen fluoride.

6. In a process for the separation and decontamination of plutonium values from an aqueous solution containing the same together with contaminating uranium fission products, comprising precipitating bismuth phosphate therein while maintaining said plutonium values in tetravalent oxidation state, to thereby carrier precipitate said plutonium values therewith, and thereafter separating the resulting plutonium-carrying precipitate from its supernatant solution, the improved method for removing contaminating uranium fission products from the separated carrier precipitate, which have accompanied the same, which comprises washing the precipitate with an aqueous solution of ammonia and hydrofluoric acid of molar ratio within the approximate range of 1:4 to 1:2.

7. In a process for the separation and decontamination of plutonium values from an aqueous solution containing the same together with contaminating uranium fission products, comprising precipitating bismuth phosphate therein while maintaining said plutonium values in tetravalent state, to thereby carrier precipitate said plutonium values therewith, and thereafter separating the resulting plutonium-carrying precipitate from its supernatant solution, the improved method for removing contaminating uranium fission products from the separated carrier precipitate, which have accompanied the same, which comprises washing the precipitate with an aqueous solution of ammonia and hydrofluoric acid in molar ratio within the approximate range of 1:4 to 1:2, and of concentration within the approximate range of 10 to 20% by weight.

8. In a process for the separation and decontamination

of plutonium values from an aqueous solution containing the same together with contaminating uranium fission products, comprising precipitating bismuth phosphate therein while maintaining said plutonium values in tetravalent oxidation state, to thereby carrier precipitate said plutonium values therewith, and thereafter separating the resulting plutonium-carrying precipitate from its supernatant solution, the improved method for removing contaminating uranium fission products from the separated carrier precipitate, which have accompanied the same, which comprises washing the precipitate with an aqueous solution of ammonia and hydrofluoric acid of molar ratio within the approximate range of 1:4 to 1:2, by means of slurring the precipitate in said aqueous solution, and thereafter separating the plutonium-carrying precipitate from the contaminant-containing wash solution.

9. In a process for the separation and decontamination of plutonium values from an aqueous solution containing the same together with contaminating uranium fission products, comprising precipitating bismuth phosphate therein while maintaining said plutonium values in tetravalent oxidation state, to thereby carrier precipitate said plutonium values therewith, and thereafter separating the resulting plutonium-carrying precipitate from its supernatant solution, the improved method for removing contaminating uranium fission products from the separated carrier precipitate, which have accompanied the same, which comprises successively washing the precipitate a plurality of times with an aqueous solution of ammonia and hydrofluoric acid of molar ratio within the approximate range of 1:4 to 1:2, with each washing being conducted by slurring the precipitate in the wash solution and thereafter separating the plutonium-carrying precipitate from the contaminant-containing wash solution.

10. In a process for the separation and decontamination of plutonium values from an aqueous solution con-

taining the same together with contaminating uranium fission products, comprising precipitating bismuth phosphate therein while maintaining said plutonium values in tetravalent oxidation state, to thereby carrier precipitate said plutonium values therewith, and thereafter separating the resulting plutonium-carrying precipitate from its supernatant solution, the improved method for removing contaminating uranium fission products from the separated carrier precipitate, which have accompanied the same, which comprises washing the precipitate with an aqueous solution of ammonia and hydrofluoric acid of a molar ratio within the approximate range of 1:4 to 1:2, separating the plutonium-bearing precipitate from the contaminant-containing wash solution, and thereafter washing the separated precipitate with water.

11. In a process for the separation and decontamination of plutonium values from an aqueous solution containing the same together with contaminating uranium fission products, comprising precipitating bismuth phosphate therein while maintaining said plutonium values in tetravalent oxidation state, to thereby carrier precipitate said plutonium values therewith, and thereafter separating the resulting plutonium-carrying precipitate from its supernatant solution, the improved method for removing contaminating uranium fission products from the separated carrier precipitate, which have accompanied the same, which comprises washing the precipitate with an aqueous solution of ammonia and hydrofluoric acid of a molar ratio within the approximate range of 1:4 to 1:2, and thereafter washing the plutonium-carrying precipitate, which has consequently been subject to some conversion to bismuth trifluoride, with an aqueous solution of an alkali hydroxide, to thereby beneficially purge the plutonium-carrying precipitate of fluoride ion.
